CLASSIFIER

James Macdonald Mitchell, Flushing, N. Y.

Application January 3, 1929. Serial No. 330,051

12 Claims. (Cl. 209—429)

This invention relates to classifiers and, more particularly, to apparatus for classifying and dewatering fine material carried in a liquid.

The principal object of the invention is to provide apparatus for the treatment of fine material in a liquid to effect a classification of the material and simultaneously remove the liquid therefrom.

Another object is to provide apparatus of the character above set forth which includes a conveyor in the form of a belt upon which the material to be classified is deposited and which is of such construction that in the course of travel of the belt, liquid will drain from the material and the material will settle upon the belt and will be classified as coarse, medium and fine.

A further object of the invention is to provide apparatus of the character set forth including a belt conveyor which is trough-shaped or concave in cross-section and which travels over idlers which can be adjusted angularly to vary the depth of the trough and thereby vary the rate of flow of the liquid over the belt and, consequently, the quantity and character of the material settled out.

Other objects and advantages of the invention will in part be obvious and in part more fully brought out as the description proceeds.

In the accompanying drawings, I have illustrated a practical embodiment of my invention; but it is to be understood that the drawings are illustrative merely and are not to be construed as limiting the invention to the particular details of construction therein shown. It will be readily appreciated by those skilled in the art that the invention is susceptible of embodiment in a variety of forms without sacrificing any of the advantages of the invention or departing from the scope thereof as defined in the appended claims.

In these drawings:

Fig. 1 is a plan view of a classifying apparatus constructed in accordance with my invention;

Fig. 2 is a sectional view taken substantially on line 2—2 of Fig. 1; and

Fig. 3 is a sectional view taken substantially along line 3—3 of Fig. 1.

Referring, now, to the drawings, the reference-numeral 1 indicates generally a frame-work which may be of any suitable construction and which is composed of uprights and cross-pieces suitably arranged to form a rigid supporting frame.

Suitably mounted in the frame at one end is a drive roll or pulley 2 which is driven by a belt 3 which receives its motion from any convenient

source of motive power. At the opposite end of the frame is mounted a head-pulley or roller 4, and at the lower end of the frame are mounted guide-rolls 5 and 6.

The reference-numeral 7 indicates generally a conveyor of the endless type which is trained about the drive-pulley or roller 2 and the head-pulley 4, and which is suitably guided in its movement by the guide-rollers 5 and 6. The conveyor 7 may be in the form of a continuous, one-piece belt, provided along its longitudinal center with openings 8 for the escape of liquid. However, I prefer to construct the conveyor 7 of two belts of equal length and which are so trained about various pulleys as to provide space between their adjacent edges and thus produce a continuous discharge opening for the liquid. The two belts are secured in spaced relation by means of suitable securing elements or straps 9 which are riveted or otherwise fastened to the respective belts. By this means, the conveyor, although constructed of two separate belts, is in fact a unitary structure and travels as such during the operation of the apparatus.

Upon the upper part of the framework, I have provided a plurality of idlers 10 which support the upper or operating portion of the conveyor.

As indicated in Fig. 2, the idlers 10 are mounted in pairs upon supports 11 which are pivoted as at 12 to certain cross-pieces of the framework. Upon the bottom surface of each of the supports 11 I have provided an inclined projection or wedge 12 which cooperates with a movable wedge 13, the arrangement being such that as the wedge 13 moves inwardly or outwardly with respect to the center of the apparatus, the supports 11 will be elevated or lowered by reason of their turning movement about their respective pivots 12. The wedges 13 are operated by means of a screw-rod 14 provided with a hand-wheel 15 which extends beyond the framework 1 and is thereby easily accessible to the operator.

By an inspection of the above-described arrangement as disclosed in Fig. 2, it will now be apparent that the contour of the conveyor 7 may be varied by adjustment of the idlers 10. In actual operation of the apparatus, the idlers 10 will be so adjusted as to impart to the conveyor a concave cross-sectional area. In other words, the conveyor may be said to be trough-shaped. By moving the wedges 13 outwardly from the center of the apparatus, it will be seen that the inner idlers 10 will be proportionately lowered and, thus, a more decided trough is imparted to the conveyor. The purpose of this

arrangement will hereinafter be more fully pointed out.

For supplying material, such as sand in a liquid, to the conveyor, I have provided feed boxes 16 at opposite edges of the conveyor near the driving end thereof. The material flows from the feed boxes 16 to the conveyor 7 over inclined aprons 17.

When the material is deposited upon the conveyor 7, it will be apparent that the liquid will flow towards the center of the conveyor and will escape through the openings 8 and will be collected in a waste-water launder 18 suitably supported in the framework 1. By reason of the slope of the sides of the conveyor towards the center, it will be apparent that since the outside edges have the greatest departure from the horizontal, the speed of travel of the water will decrease as it flows towards the center. The rate of flow of the water is also affected by the fact that it will spread out and, consequently, be more shallow near the center, and there will be some loss of speed due to friction. The result is that when the material, for example sand in a liquid, is deposited upon the edges of the conveyor, the liquid will start to flow towards the center thereof. The coarser particles of the material will at once settle upon the conveyor near the outer edge and the grade of material will become gradually finer towards the center of the conveyor by reason of the fact that more time is allowed for the material to settle out. Of course, the very finest particles will be carried by the liquid through the openings 8 and into the waste-water launder 18.

During the operation of the apparatus, it is, of course, understood that the conveyor travels in a horizontal plane from right to left, as indicated in Fig. 3. During the course of its travel, the liquid constantly flows down the sides of the conveyor and into the escape openings, with the result that when the material reaches the head-pulley 4, it has been substantially de-watered and is arranged upon the conveyor in such a manner that the coarser particles are near the outside edges thereof and the finer ones near the center. As the conveyor travels over the head-pulley 4, the material drops off and is collected in suitable hoppers 19.

The depths of the trough of the conveyor 7 may be varied from time to time by adjustment of the idlers, as heretofore described, so as to render the apparatus useful for any desired classification. For example, if it is desired to settle out only coarse sand from the material fed to the conveyor, the idlers will be so adjusted as to provide a trough of such depth that the liquid will flow rapidly through the discharge openings. This will permit only sufficient time for the settling of the heavier or coarser particles. If a very fine classification of the material is desired, the trough will be made very shallow, so as to provide for a slow flowing of the liquid towards the discharge openings. This will give even the finer particles sufficient time to settle out of the liquid and to be deposited upon the conveyor.

It is believed that my invention has now been fully brought out and that its many advantages will be readily apparent and appreciated by these skilled in the art. As heretofore indicated, I do not confine myself to the particular structure herein described and illustrated in the accompanying drawings, but may avail myself of any

modifications thereof which will come within the scope of the appended claims.

What I claim is:

1. Apparatus for classifying material in a liquid, including a pair of belts spaced to provide between them an opening for the escape of liquid, means for imparting motion to said belts, means to maintain said belts in predetermined spaced relation and effective to cause said belts to move as a unit, and means for varying the angular relation of the belts. 80 85

2. Apparatus for classifying material in a liquid, including a pair of angularly related belts, means connecting and maintaining the belts in spaced relation as a unit, means for supporting each of said belts, and means for adjusting said supporting means to vary the angular relationship of the belts. 90

3. Apparatus for classifying material in a liquid, including a conveyor composed of a pair of belts connected together in spaced relation, means for supporting each of the belts, and means for adjusting said supporting means to vary the contour of said conveyor. 95

4. Apparatus for classifying material in a liquid, including a conveyor composed of a pair of spaced belts connected at intervals, a plurality of independent angularly adjustable idlers for supporting said belts, and means to adjust the angular relationship of certain of said idlers whereby to vary the contour of said conveyor. 100 105

5. Apparatus for classifying material in a liquid, including a pair of angularly related belts connected together in spaced relation, a plurality of pairs of angularly adjustable idlers for supporting said belts, and means to adjust the angular relationship of the idlers of each pair to thereby vary the angular relationship of the belts. 110

6. Apparatus for classifying material in a liquid, including a frame, rollers supported in said frame, an endless conveyor trained about said rollers and composed of a plurality of belts connected together in spaced relation, a plurality of idler supports pivotally mounted on said frame between said rollers, idlers on said supports, and means for turning said supports about their respective pivots to vary the angle of the idlers and thereby vary the cross-sectional contour of said conveyor. 115 120 125

7. Apparatus for classifying material in a liquid, including a frame, rollers supported in said frame, an endless conveyor trained about said rollers, a plurality of idler supports pivotally mounted on said frame between said rollers, idlers on said supports, a wedge secured to each of said supports, and movable wedges mounted in said frame and adapted to cooperate with the wedges on said supports to turn said supports about their respective pivots. 130 135

8. Apparatus for classifying material in a liquid, including an endless conveyor of concave transverse cross-section and provided with openings located centrally between its edges for the escape of liquid, and means for depositing material in a liquid upon said conveyor at the outer edges thereof, whereby the liquid will flow at gradually decreasing speed toward said escape openings and the material will be gradually deposited upon said conveyor, the coarser material at the edges and the finer material nearer to the escape openings. 140 145

9. Apparatus for classifying material in a liquid including a conveyor composed of a pair of endless belts connected at intervals by cross 150

pieces, supporting means for each of the belts, and means for varying the angular relation of the supporting means to vary the cross sectional contour of the conveyor.

5 10. Apparatus for classifying material in a liquid including an endless conveyor formed with central discharge openings, supporting members disposed beneath the conveyor on each side of the discharge openings, and means for varying the angular relation of the supporting members to vary the cross sectional contour of the conveyor.

10 11. Apparatus for classifying material in a liquid, including a belt conveyor having a central longitudinal opening dividing the conveyor into spaced longitudinal sections, idler rolls supporting each section of the conveyor for a substantial portion of its width inwardly of its edges, the rolls at their inner end terminating short of the

opening between the sections, and means to adjust the idlers to vary the contour of the conveyor and cause the respective sections to incline towards the central opening.

12. Apparatus for classifying material in a liquid, including a frame, rollers supported in said frame, an endless conveyor having an opening located centrally between its edges dividing the conveyor into longitudinal sections trained about said rollers, a plurality of angularly adjustable idlers mounted upon said frame between said rollers for supporting each section of the conveyor, said idlers extending for a substantial portion of the width of the conveyor sections but terminating short of the central opening, and means to adjust said idlers to vary the cross-sectional contour of said conveyor relative to the central opening.
